(57) **CLAIM**

The ornamental design of a muscle toning body device, as shown and described.

DESCRIPTION

FIG. 1 is a front perspective of the present invention.

FIG. 2 is right side view of the present invention.

FIG. 3 is a left side view of the present invention.

FIG. 4 is a back view of the present invention.

FIG. 5 is a front view of the present invention.

FIG. 6 is a top view of the present invention; and,

FIG. 7 is a bottom view of the present invention.

The broken lines depict portions of the muscle toning body device that form no part of the claimed design.

1 Claim, 5 Drawing Sheets
